UNITED STATES PATENT OFFICE.

SEBASTIAN ZIANI DE FERRANTI, OF GRINDLEFORD BRIDGE, SHEFFIELD, ENGLAND.

BLADED TURBINE ELEMENT.

No. 874,398.

Specification of Letters Patent.

Patented Dec. 24, 1907.

Original application filed May 14, 1904, Serial No. 208,034. Divided and this application filed July 22, 1907. Serial No. 385,056.

To all whom it may concern:

Be it known that I, SEBASTIAN ZIANI DE FERRANTI, a subject of the King of Great Britain and Ireland, residing at Grindleford Bridge, Sheffield, in the county of York, England, (late of 31 Lyndhurst road, Hampstead, London, N. W., England,) have invented a certain new and useful Bladed Turbine Element, of which the following is a specification.

The invention relates to the bladed elements of turbines and has for its object the provision of a bladed turbine element of exceedingly simple construction as regards the attachment of the blades so that calking strips, lacing or wiring and other complex means employed for fixing the blades may be dispensed with.

A turbine element with the blades welded thereon has hitherto been a desideratum since such a bladed turbine element approaches closely to the ideal form shaped from a solid mass of metal. Difficulties, however, exist in the production of such a bladed turbine element partly on account of the blades and their carrying elements differing largely as regards their power of conducting heat away from the welding point and partly on account of the close juxtaposition of the blades. Thus it is found that the comparatively large volume of metal forming the carrier rapidly conducts heat away from the welding point and prevents the temperature of the carrier rising to the required extent. I overcome all these difficulties, however, by a process described in my patent application, Serial No. 208034, which consists broadly in adjusting the volume of the metal in the neighborhood of the welding point so that approximately equal heating occurs in both faces to be welded and passing electric current through the welding point.

I believe that I am the first to produce a turbine element with the blades directly welded thereto and such a bladed turbine element forms the subject matter of the present invention.

Referring to the accompanying drawings, Figure 1 is a part side elevation of a turbine wheel having cross grooves, Fig. 1^a being an edge view; Fig. 2 shows a similar edge view of a modification in which sets of intersecting grooves are adopted; Fig. 3 shows an edge view of a form having circumferential grooves,

Fig. 3^a being a section on the line A A of Fig. 55 3. Fig. 4 shows, in longitudinal sectional elevation, part of a drum carrier to which the blades are welded in accordance with one form of the invention; Figs. 5 and 6 show edge views of modifications in which holes 60 are bored radially into the edge of the disk, while Fig. 7 is a part side elevation in which holes are bored through from face to face of the disk. Fig. 8 shows a sectional plan of a form of wheel built up of two dished disks, 65 held apart at their circumferential portions by distance pieces, Fig. 8^a being a scrap edge view to a larger scale; Fig. 9 is a similar sectional plan of a modified form of wheel built up of three disks, while Fig. 9^a is a corresponding scrap edge view also to a larger scale; Fig. 10 shows a part sectional elevation of a wheel built up of two comparatively thick disks having notched edges. Fig. 10^a being a scrap edge view, while Fig. 70 75 Fig. 11 shows an edge view of a form of wheel built up of a series of "stepped" laminæ.

(It will be seen that all the edge views in the preceding figures are shown as developments for clearness of drawing and not as true projections).

In carrying out the invention according to the form shown in Figs. 1 and 1^a, the turbine wheel or disk is shown at a, cross grooves, b, being cut in its circumferential edge so as to 85 leave projecting portions of metal, c, to which the turbine blades, d, are welded. The same object is attained by cutting two intersecting sets of grooves, e, in the edge of the disk, as is shown in Fig. 2, or by cutting 90 circumferential grooves, such as f, completely round the edge (see Figs. 3 and 3^a).

Fig. 4 shows the invention according to one form applied to the case of a drum blade carrier, a'; the drum is grooved circumferentially with grooves, f', the intervening collars of metal being then cross-cut to form 95¹ projecting teeth, c', on which the blades are welded.

According to a modified form, radial holes, 100 h, may be bored a short distance into the edge of the disk, these holes being either arranged in patterns so as to leave intervening projections of untouched metal to which the blades may be welded as shown in Fig. 5, or 105 arranged without particular reference to the position of the blades, (see Fig. 6).

In Fig. 7, a method is shown of removing

metal in the neighborhood of the welding point by boring holes, *i*, through (or partly through) from face to face of the disk at a radius slightly less than that of its outside edge.

The object to be kept in mind in this as in other modifications, is to remove sufficient metal to enable the temperature to rise to the welding point as explained above, while 10 at the same time leaving sufficient areas untouched to insure the mechanical strength in the welded joint.

Referring now to Figs. 8 and 8^a, a form of wheel is shown somewhat diagrammatically which is built up of two dished disks, *k*, of comparatively thin metal, held apart at their circumferential portions by one or more distance pieces, such as *l*, disposed at a radius somewhat less than the maximum radius of the 20 disks, the blades, *d*, being welded in position on their outside edges.

Figs. 9 and 9^a show a type of wheel generally similar to that last described but having an intermediate plane disk, *m*, in addition to the two dished disks, *k*; a portion, *n*, of the hub, *o*, is in this case made detachable so as to allow the different parts of the wheel to be assembled. Distance pieces, *l*, are indicated as before but any other convenient 30 method of holding the disks in their correct relative position may be adopted.

In Figs. 8 and 9, the dished disks, *k*, are indicated as secured to the hubs, *o*, by pressing the inner edges of these disks into grooves and subsequently burring over the hubs to hold the disks in place.

In the modification shown in Figs. 10 and 10^a, two dished disks, *k*, are again employed but of thicker metal, their circumferential 40 portions being brought into contact and cross grooves, *b*, being cut in their edges in accordance with the method described above with reference to Figs. 1 and 1^a. Again, that portion of the disk carrying the blades 45 may be built up of a set of thin laminae, *r*, (see Fig. 11), the edges of which are notched as at *s*; the laminae being assembled in such a way that the notches, *s*, are "stepped" with regard to each other, so that the intervening 50 projections of metal may follow the shape of the turbine blades to be welded to them.

Instead of notching the laminae, they may be prepared in accordance with other of the methods pointed out above, before being 55 assembled in the manner indicated.

In this invention, it is not practicable to describe every method of carrying its broad underlying principle into effect, but the scope is sufficiently indicated by the many 60 examples given above and moreover it will be evident without further description, how the invention may be applied to the welding together of turbine blades and carriers of other forms than those described above by 65 way of example.

Having now described my invention what I claim as new and desire to secure by Letters Patent is:—

1. A turbine blade carrier having blades welded directly thereto. 70
2. A turbine blade carrier with blades attached thereto wholly by welding.
3. A turbine blade carrier having blades attached thereto by welds, certain working stresses on said blades being transmitted to 75 said carrier through said welds.
4. A turbine blade carrier having blades attached thereto by welds, certain bending stresses due to impact of fluid on said blades being transmitted to said carrier through 80 said welds.
5. A turbine rotor having blades attached thereto by welds, certain working stresses on said blades being transmitted to said rotor through said welds. 85
6. A turbine blade carrier having blades attached thereto by welds and recesses in the carrier in the neighborhood of said welds.
7. A bladed turbine element, comprising in combination a blade carrying element, the 90 volume of the peripheral portion of which in the neighborhood of the point of attachment of the blades has been so adjusted as to retard flow of heat away from said point of attachment together with blades welded to 95 said carrying element.
8. A bladed turbine element comprising in combination a blade carrying element from the peripheral portion of which metal has been removed in the neighborhood of the 100 point of attachment of the blades so as to retard flow of heat away from said point of attachment together with blades welded to said carrying element.
9. A bladed turbine element comprising in 105 combination a blade carrying element having depressed portions on its peripheral area with intervening portions raised relatively to said depressed portions and blades welded to said relatively raised portions. 110
10. A bladed turbine element comprising in combination a body portion, blade carrying members proper attached to said body portion by one face and having blades welded to an opposite face together with spaces 115 intervening between said blade carrying members proper.
11. As a new article of manufacture, a bladed turbine element having a plurality of spaced blades attached to the periphery of 120 said carrier by direct butt welds.
12. A bladed turbine element comprising in combination a blade carrying element having a circularly disposed aggregation of depressed portions alternating with relatively 125 raised portions and blades welded to said relatively raised portions.
13. A bladed turbine element comprising in combination a body portion; a circularly disposed aggregation of blade carrying mem- 130

bers proper attached to said body portion by one face and having blades welded to an opposite face together with spaces intervening between said blade carrying members proper.

- 5 14. A bladed turbine element comprising in combination a blade carrying element having a plurality of raised portions regularly spaced along said carrying element and blades welded to said raised portions.
- 10 15. A bladed turbine element comprising in combination a circular blade carrying ele-

ment having a peripheral portion, a plurality of raised portions regularly spaced along said peripheral portion and blades welded to said raised portions.

15

In testimony whereof, I affix my signature in presence of two witnesses.

SEBASTIAN ZIANI DE FERRANTI.
